UNITED STATES PATENT OFFICE.

THEODORE ABBOTT, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,068, dated July 25, 1882.

Application filed June 14, 1882. Term of patent 14 years.

To all whom it may concern:

Be it known that I, THEODORE ABBOTT, of the city and county of Philadelphia, in the State of Pennsylvania, have invented and 5 produced a new and original Design for Fringe, of which design the following is a specification.

The accompanying drawing is a side view of a section of fringe embodying and illustrating my design, which consists in a fringe having a heading, A, to which is attached a series of chenille pendants, B, ornamented by the following arrangement of colors in the threads of which they are composed, to wit: A portion, b—say about one-half of the length of 10 the pendant—is formed of threads of a uniform and regular color or combination of colors throughout—that is, the whole of the por-

tion b will be of a single color, unvarying in depth, or be uniformly dotted or mottled. 20 The remainder of the pendant is made up of a series of stripes, belts, or bands, b', of two or more different colors, said series of stripes presenting the appearance or effect of a variegated border or frieze upon the fringe. 25

I claim—

A design for fringe, consisting of pendants which for a portion of their length are of a uniform and unvarying color or combination of colors, and for the remainder are striped, 30 belted, or banded in two or more colors, substantially as set forth.

THEODORE ABBOTT.
